UNITED STATES PATENT OFFICE.

JOHN W. COX, OF ERIE, PENNSYLVANIA.

FIRE-PROTECTION SYSTEM.

1,205,517.

Specification of Letters Patent. Patented Nov. 21, 1916.

Application filed May 9, 1913. Serial No. 766,511.

To all whom it may concern:

Be it known that I, JOHN W. COX, a subject of the King of Great Britain, having declared my intention of becoming a citizen 5 of the United States, residing at Erie, in the county of Erie and State of Pennsylvania, have invented new and useful Improvements in Fire-Protection Systems, of which the following is a specification.

10 This invention relates to fire protection systems and consists in certain improvements in the construction thereof as will be hereinafter fully described and pointed out in the claims.

15 The object of the invention is to provide a fire protection system which may be readily controlled at points remote from the devices controlling the water in the water distributing system.

20 In the preferred form the invention relates to a system in which the distributing mains are normally dry and the apparatus is designed to turn the water into this normally dry system, indicate the hose boxes 25 and also for indicating at the points from which the water is turned in the fact that the controlling apparatus has been actuated.

The system also involves further devices 30 in connection with this general scheme as will appear more fully from the specification and claims.

The invention is illustrated in the accompanying drawings as follows:

Figure 1 shows an outline of the system of 35 the controlling mechanisms. Fig. 2 is a front elevation, partly in section showing the clock mechanism. Fig. 3 is a side elevation of the same. Fig. 4 is a central section through the cylinder controlling mechanism 40 for indicating the flow of water in the distributing system. Fig. 5 is an enlarged view, partly in section of the main gate valve and controlling mechanism therefor for the water system.

45 Water is delivered from the main by way of the pipe 1. It passes the gate valve 2 and is accelerated or forced by the pump 3 and extends to the distributing system 4. A hose branch 5 is controlled by the valve 6 and the hose box 7 is provided usually containing a hose (not shown) in direct connection with the branch 5.

Current is supplied from the generator 8^a or any convenient source and is connected through the circuit formed by the wires 8 55 and 9. A branch line 10 extends from the line 9 to a light, ordinarily a white light 11. The circuit is continued through a line 12 by way of a switch 13, switch lever 14 and line 15 to the line 8 completing the circuit. 60 From this it will be seen that the light 11 is normally in circuit and indicates the position of a push button 16. While but one of these is shown it will be understood that these are distributed and at convenient locations. 65

The apparatus is set in motion by the push button 16. The switch controlled by the switch button is connected at one side by the line 17 with the line, 10 heretofore described which connects this side of the button with the line 9. The opposite side of the button has a line 18 and this passes by a branch 18^a through a magnetic coil 19 and thence by a line 20 closing the circuit 75 with the line 8. As soon as the current is turned on through this circuit, a latch 21 is drawn down by the magnet 19. This latch is pivoted at 22 and releases the switch lever 23. The switch lever has a contact post 24. 80 It is pivoted at 25 and connected by a line 27 with the wire 10, thus closing one side of the circuit with the line 9. The lever 23 is under the influence of a spring 26 which tends to draw it forward so that when it 85 is released by the latch 21 the lever swings forward carrying the post 24 into contact with the post 28 and closing the circuit between the lines 27 and 29. The line 30 is connected with the line 29 and connects to a 90 solenoid 31, the return line 32 being connected with the line 33 which returns to the line 8 thus completing the circuit through the solenoid 31. The core 34 of the solenoid forms an extension of the stem of a gate 95 valve 35 so that when the current is turned through the solenoid, the valve 35 is opened turning the water from the main 1 through the pipe 36 into the passage 37 and thence to the cylinder 38. A piston 39 is arranged 100 in the cylinder 38 and connected by a stem 40 with the gate 41 of the gate valve 2. It will be observed, therefore, that as the water is turned on by way of the valve 35 into the

cylinder 38, the main gate valve 2 is opened thus turning water into the system. A stem 42 extends from the piston by means of which the gate valve may be closed.

- 5 In many systems it is desirable to accelerate the flow from the main. This is accomplished in the present device as follows:—The line 28 heretofore referred to extends through a solenoid 48, the other side 10 of the solenoid being connected with the line 38. In this way the circuit is closed through the solenoid upon the operation of the push button. The movable element of the solenoid is connected to a switch lever 44 of a 15 rheostat, the switch lever passing over the contacts 45. One side of the rheostat is connected by a line 46 with the line 8 and the other side is connected by way of the lever 44 which is pivoted at 47 with a line 48. 20 The line 48 is carried through a motor 49 and thence by way of a line 50 is connected with the line 9 thus completing the circuit. It will be readily seen that as the push button is operated the current is turned on 25 through the circuit formed by the lines 29 and 33 by means of the switch 24 and the rheostat is operated starting the motor 49 and thus the pump which is of the ordinary rotary type. As the water is turned on a 30 light 51 is turned in through the lines 52 and 53 connecting with the lines 29 and 33. It is desirable when the device is thrown into operation that an alarm be carried to some point as desired, as for instance, the 35 office of the factory. This is supplied in the present system by the following mechanism:—The line 18 extending from one side of the push button is connected by a line 54 with the magnetic coils 55 and the circuit 40 completed by the line 56 connecting the coil with the line 8. The armature 57 of the magnet forms a latch which is pivoted at 58 and when operated releases the switch lever 59. This switch lever is pivoted at 60 45 and has one side connected by a line 61 through a battery 62 with an alarm bell 63, the line 64 extending from the bell to a post 65. The lever 59 carries a post 66 and when the latch 57 is operated the post 66 is thrown 50 into contact with the post 65 by the action of a spring 67 so that the circuit is closed through the battery and the alarm from the bell 63 is given.

- 55 It is desirable that the person operating the push button should be assured that the mechanism controlling the water in the system has operated when the push button is actuated. This is accomplished in this apparatus as follows:—A pipe 68 is connected 60 with the distributing system 4 and, therefore, has liquid under pressure or is dry depending upon the condition of the system, this pipe extending to a cylinder 69. The cylinder has the piston 70 from which extends 65 the rod 71. The rod 71 is connected

with the yoke 71^a and springs 72 are secured to the opposite ends of the yoke and the cylinder and tend to hold the piston normally in a lower position. The pin 73 extends from the yoke 71^a through a slot 74 in the switch lever 14. The switch lever 14 is pivoted on a pin 75. This lever is normally in contact to close the switch 13 so as to maintain current in the light 11. When, however, water is turned into the system 4 it 75 passes by way of the pipe 68 to the cylinder 69 and operating on the piston 70 forces the yoke 71^a upwardly and thus one end of the lever 14 upwardly. This throws the switch controlled by the opposite end of the lever 80 out of contact thus cutting off the current from the light 11 and closing the circuit through the post 76. The post 76 is connected by a wire 77 with a light 78, preferably of different color from the light 11, and the 85 opposite side of the light is connected by the line 10 with the line 9. The circuit is completed from the post 76 through the switch lever 14, line 15 with the line 8. It will be readily seen, therefore, that the operator 90 pushing the button 16 is almost instantly apprised of the action of the controlling mechanism. If it has operated the white light 11 is extinguished and the light 78 turned on. If, however, the water has not 95 been turned into the line this change does not take place and the person operating the button is apprised of this fact.

It is desirable to supplement this indicating mechanism with an alarm which will 100 be operative in case the controlling mechanism fails to turn on the water upon the operation of the push button. The reason for this is that if there is such failure on the part of the automatic mechanism operators 105 adjacent to the valves on the main line may manually turn on the water. It is desirable ordinarily that this alarm shall not be given provided the water is turned in through the apparatus. To accomplish this purpose, I 110 have provided the following mechanism:—The magnetic coil 79 is connected with the line 18 and the opposite side of the coil is connected by a wire 80 with the line 8. It will be readily understood that the circuit 115 is closed through this coil and is closed on the button 16 by way of the line 17 and the lines 10 and 9. The armature 81 of the coil 79 is pivoted at 81^a and controls the latch 82 which is normally arranged in the path of one of the vanes of a controlling fan or retarding device 83. The fan blades are carried by a shaft 84, the shaft being journaled in a frame 85. The pinion 86 is fixed on the shaft 84 and meshes a 120 gear 87. The gear 87 is journaled on a shaft 88, the shaft having a squared end 88^a by means of which it may be actuated by a key. The shaft has a ratchet wheel 89 fixed 125 on it, the ratchet wheel being locked against 130

movement in one direction by a pawl 90 pressed into engagement by the spring 91. The spring 92 has one end attached to the shaft 88 in the usual manner and the opposite end to the wheel 89. The spring may be wound up in the usual manner, the ratchet wheel locking it against unwinding in one direction and the latch 82 normally locking it against movement in the opposite direction. A contact post 93 is carried by the wheel 89 and is adapted to engage a post 94. The post 94 is connected by a wire 95 with a gong 96, the opposite side of the gong being connected by the wire 97 with the wire 9. The line 98 is connected by the shaft 88 with a post 99 which is normally in contact with the switch lever 14. The normal position of the contact lug 93 is such that it requires considerable travel before it comes into contact with the post 94. This interval is so arranged with the retarding device and the distance that the lug 93 must travel to permit the water passing by the pipe 68 to enter the cylinder 69 in throwing the water into the system and to operate the switch lever 14. If, therefore, the water is turned on by the operation of the mechanism described when the push button is actuated it will reach the cylinder 69 throwing the switch 14 out of contact with the post 99 and thus break the circuit with the gong 96 prior to the time the lug 93 reaches the post 94. If, therefore, the apparatus operates there will be no alarm from the gong 96 but if the apparatus turning in the water fails to operate then the lug 93 coming into contact with the post 94 will close the circuit through the gong 96 and give the alarm for the purpose above described.

What I claim as new is:—

1. In a fire protection system, the combination of a water distributing system; devices controlling the flow in said system; an electric apparatus controlling said devices; a switch controlling the electric apparatus; and an indicator observable at the switch controlled by the flow of water in the system indicating the operation of said devices.
2. In a fire protection system, the combination of a normally dry water distributing system; devices controlling the flow in said system; an electric apparatus controlling said devices; a switch controlling the electric apparatus; and an indicator observable at the switch controlled by the flow of water in the system indicating the operation of said devices.
3. In a fire protection system, the combination of a water distributing system; a pump influencing the flow of water in the system; an electric apparatus controlling the action of said pump; a switch controlling the electric apparatus; and an indica-

tor observable at the switch controlled by the flow of water in the system indicating the operation of said devices.

4. In a fire protection system, the combination of a water distributing system; a pump influencing the flow of water in the system; a valve controlling the flow of water in the system; an electric apparatus controlling said pump and valve; a switch controlling the electric apparatus; and an indicator observable at the switch and controlled by the flow of water in the system indicating the operation of said pump and valve.

5. In a fire protection system, the combination of a water distributing system; devices controlling the flow of water in said system; an electric apparatus controlling said devices; a switch controlling the electric apparatus; an indicator observable at the switch comprising a motor connected with the system and adapted to be actuated by the water from the system; and an electric signaling device actuated by the motor.

6. In a fire protection system, the combination of a water distributing system; devices controlling the flow in said system; an electric apparatus controlling said devices, said electric apparatus comprising an actuating switch; a light adjacent to said switch; and a water motor connected with the distributing system controlling said light.

7. In a fire protection system, the combination of a water distributing system; devices controlling the flow in said system; an electric apparatus controlling said devices comprising a switch; a light normally in circuit adjacent to said switch; a light normally out of circuit adjacent to said switch; and a motor connected with the distributing system, said motor controlling the lights.

8. In a fire protection system, the combination of a water distributing system; devices controlling the flow of water in the system; an electric apparatus controlling said devices; an alarm; and means actuating said alarm when said apparatus is actuated with a failure of the operation of said devices and means for preventing the operation of said alarm upon the operation of said devices.

9. In a fire protection system, the combination of a water distributing system; devices controlling the flow of water in said system; an electric apparatus controlling said devices; an indicator controlled by the flow of water in the system indicating the operation of said devices; and an alarm controlled by said indicator and operating upon the failure to act of said devices with the operation of said apparatus.

10. In a fire protection system, the combination of a water distributing system; devices controlling the flow of water in said

system; an electric apparatus controlling said devices; a motor connected with the system; mechanism for throwing in an alarm; means controlled by the motor for preventing an alarm through said mechanism when said motor is actuated; and a retarding device operating in connection with said mechanism to prevent its action prior to the normal operation of the motor.

In testimony whereof I have hereunto set my hand in the presence of two subscribing witnesses.

JOHN W. COX.
